(57) **CLAIM**

The ornamental design for a ball control valve, as shown and described.

DESCRIPTION

FIG. 1 is a perspective view of the ball control valve showing our new design;

FIG. 2 is a front elevational view thereof;

FIG. 3 is a rear elevational view thereof;

FIG. 4 is a first side view thereof;

FIG. 5 is an opposite side view thereof;

FIG. 6 is a top view thereof;

FIG. 7 is a bottom view thereof; and,

FIG. 8 is another perspective view thereof.

The broken line on the figures is included for the purpose of illustrating environment and forms no part of the claimed design.
